UNITED STATES PATENT OFFICE.

FREDERICK FICKEY, JR., OF BALTIMORE, MARYLAND, ASSIGNOR TO WM. H. FICKEY, OF SAME PLACE.

IMPROVEMENT IN TOBACCO-SMOKING PIPES.

Specification forming part of Letters Patent No. 40,881, dated December 8, 1863.

To all whom it may concern:

Be it known that I, FREDERICK FICKEY, Jr., of the city of Baltimore, in the State of Maryland, have invented an Improvement in Tobacco-Pipes; and I do hereby declare the following to be a full and correct description of the same, reference being had to the accompanying drawing, in which the figure represents a vertical section through the middle of my improved pipe and its stem.

The nature of my invention consists in so arranging in a tobacco-pipe a smoke-chamber containing a sponge or other porous absorbent substance—such as cotton, wool, pumice-stone, &c.—that while sponge or other substance shall receive and retain the nicotine or oil from the burning tobacco it shall be entirely separate and removed from that portion of the pipe in which the saliva tends to accumulate, the object being to prevent the sponge or other like substance from ever being moistened by saliva, in order that its capacity for absorption shall be entirely devoted to the reception and retention of the nicotine, thus enabling it to be used longer without cleansing or removal, and preventing the nicotine from fouling the pipe or being drawn into the mouth, all as hereinafter described.

My invention further consists in the peculiar arrangement and combination of smoke-chambers, smoke-passages, and saliva-cup herein described and shown.

I am aware that sponges have sometimes been used in tobacco-pipes; but so far as I have been able to discover they have always been placed in such a position that they have absorbed both the saliva and the nicotine, and that the bitter and acrid mixture would be drawn into the stem, and thence into the mouth, in the process of smoking. Thus after a short time the sponge rendered the pipe more foul and offensive than it would have been

without it by accumulating the saliva and nicotine at the point where they would be most injurious.

The object of my improvements has been to deprive the smoke of heat by passing it through a variety of chambers and passages, and to free it from nicotine and saliva, so that it shall reach the mouth cool and pure and incapable of producing an irritating or excoriating effect upon the mucous membrane.

The drawing clearly shows the structure of my improved pipe, A being the bowl; B, the upper smoke-chamber, filled with sponge or other similarly-acting substance; C, the second, and D the lower, smoke-chamber; E, the saliva-cup, and F the tube or stem. *a*, *b*, *c*, and *d* mark the smoke-passages, so arranged that the smoke has to traverse each chamber before descending to the succeeding one.

Having thus fully described my invention, what I claim, and desire to secure by Letters Patent, is—

1. The combination and arrangement of the chambers A, B, C, and D, the smoke-passages *a*, *b*, *c*, and *d*, and the saliva-cup E, in the manner described and shown.

2. Placing a sponge or similar material in such a position in a tobacco-pipe that while it shall absorb and retain the nicotine it shall not be liable to come in contact with and absorb the saliva which may accumulate in the pipe, substantially in the manner and for the purpose described, irrespective of any special form or arrangement of chambers, so long as the principle herein set forth is maintained.

The above specification of my said invention signed and witnessed, at Washington, this 5th day of November, A. D. 1863.

FRED FICKEY, JR.
